UNITED STATES PATENT OFFICE.

FRANCIS X. ST. LOUIS AND ALFRED M. JACKSON, OF COLUSA,
CALIFORNIA.

VOTING-MACHINE.

SPECIFICATION forming part of Letters Patent No. 752,307, dated February 16, 1904.

Application filed October 24, 1902. Serial No. 128,678. (No model.)

To all whom it may concern:

Be it known that we, FRANCIS X. ST. LOUIS and ALFRED M. JACKSON, citizens of the United States, residing at Colusa, in the county of Colusa and State of California, have invented 5 certain new and useful Improvements in Voting-Machines, of which the following is a specification.

Our invention relates to improvements in 10 voting-machines, the object of our invention being to provide a machine of this character which will be simple in construction, of convenient shape for the operation of voting; which can be built up in sections, so as to permit of being increased or diminished in size, according to the number of candidates nominated 15 in the election; which will permit of votes being cast for candidates not nominated; which will accurately register the number of 20 votes cast for each candidate, the totals being presented in convenient form for inspection at the close of the polls; which will permit a voter to withdraw a vote cast for any candidate and in place thereof to vote for another 25 candidate, and which will prevent a voter voting for more candidates of a group of candidates than the law permits.

Our invention also provides convenient 30 means for resetting the machine in readiness for the next voter.

Our invention therefore resides in the novel 35 construction, combination, and arrangement of parts for the above ends hereinafter fully specified, and particularly pointed out in the claims.

In the accompanying drawings, Figure 1 is a 40 perspective view of the machine, the rods for resetting it being broken. Fig. 2 is a broken side elevation of a section of the machine. Fig. 3 is an end view of said section. Fig. 4 is 45 an enlarged plan view of a section, parts being broken away in succession to show the mechanism. Fig. 5 is a broken plan view of an interlocking mechanism to be used where only a single candidate of a group may be voted for. Fig. 6 is a detail showing a mode of connection of the ends of two such interlocking mechanisms. Fig. 7 is a broken side elevation of an interlocking mechanism to be

used where several candidates of a group are 50 to be voted for. Fig. 8 is a broken cross-section of Fig. 4. Fig. 9 is a cross-section showing the interlocking mechanism at the bottom of the machine. Fig. 10 is a broken side view of the slide for actuating the registering mechanisms. Fig. 11 is a detail view showing a voting-stem engaging the interlocking mechanism for a plurality of candidates. Fig. 12 is a detail view of the same in another position. Fig. 13 is a side view showing the finger 60 on the stem for the interlocking mechanism for a single candidate. Fig. 14 is a cross-section showing a modified form of interlocking mechanism. Fig. 15 is a broken longitudinal section of the same. 65

Referring to the drawings, it will be seen that our improved machine is box-like in form, standing on the floor of the voting-booth, and of convenient height to permit of the voter when standing by the side of the machine to 70 read the names of the candidates and to cast his vote by operating keys for the candidates of his choice. The machine is narrow in proportion to its length; but its size will vary according to the nature of the election for which 75 it is to be used. For this purpose of thus varying its size the machine is built up in sections, each section being complete in itself, so far as the counting mechanism and the locking device are concerned, and the sections are 80 assembled like blocks to build up the machine. Suitable means, as will be hereinafter described, are provided for connecting the mechanism of the assembled sections, especially the locking mechanism. When the sections are 85 so assembled, sides 1 and ends 2, of suitable dimensions, are secured around the mechanism and framework of the machine. Upon the top 3 of each section are marked, as shown at 5, on one side of the voting-keys 16 the names 90 of the candidates to be voted for. Opposite to said keys and names are square apertures 6 in the top plate 4, through which at the close of the poll are inspected the totals cast for the nominated candidates, which can then be read 95 off and taken down by the election officers. These apertures are normally closed by a slide 7, having apertures 8 spaced at intervals sub-

stantially equal to the width of the apertures, said intervening spaces of the slide normally closing the apertures 6 during the election; but at the close of the polls the slides are by 5 the election officer pushed back sufficiently to expose the totals through the apertures 6. This may be done by means of a projecting handle 50.

At one side of the voting-keys provision is 10 made for voting for candidates not nominated. This is effected by means of a series of bands 10, of paper, which are carried around rollers 11 and are brought over a flat support 12, immediately under apertures 13 in the top 4, said 15 apertures being normally closed by means of shutters 14. By means which will be presently described these shutters are in the operation of voting withdrawn to open the apertures, permitting the voter to write upon the 20 bands of paper seen through said apertures the names of the unnominated candidates for whom he desires to cast his vote.

The act of voting consists in raising a stem 25 by means of a key 16 and giving said stem a quarter-turn either to the right or to the left and then releasing said stem. In either case a finger 17, which before voting extended in the longitudinal direction of the machine, will now extend transversely and will have dropped 30 into the upper portion of a slot 18 in a slide 19. From what has been said it will be understood that there are two such slides 19, one on either side of the row of voting-keys. One of the slides corresponds to the nominated candidates and the other to the unnominated. It will now be seen how the shutter 14 is drawn away from the aperture 13. This is done by means of a pin 20 on an arm 21 of said shutter engaged by a slotted arm 22, extending 40 from the voting-stem. The quarter-turn given to the voting-stem is sufficient to move the pin 20 and shutter 14 backward a sufficient distance to open the aperture 13.

The act of voting is completed by the election officer as the voter leaves the voting-booth. The election officer operates a handle 23, which vibrates a number of levers 24, pivoted at 25 on a frame 26, the upper ends of said levers being attached by means of rods 27 to 50 the slides 19, and thus reciprocating said slides. The upper portions of said slots are oblique in direction, and for this reason the first movement of the reciprocation has the effect of depressing those fingers 17 which had been 55 dropped by the act of voting into the upper ends of the slots. Said fingers are sufficiently long to extend through said slides over pins 28, extending from the sides of rollers 11 29, so that the depression of the fingers by their 60 engagement with said pins depresses also said pins and imparts partial rotation to the rollers. The rollers 11 on one side are those heretofore mentioned, which carry the bands of paper on which to write the names of scattering or un- 65 nominated candidates, so that in regard to

votes cast for such candidates the act of the election officer has the effect of advancing the band or bands of paper a sufficient distance to bring a clean surface below the aperture for the next voter to vote by means thereof, if 70 desired.

Upon the rollers 29 on the opposite side of the voting-keys are carried tapes or bands 30, having the numerals printed thereon from "0" up to "200" or "300" or whatever may be 75 the number of voters in the precinct, and the depression of the pins imparting partial revolutions to the rollers 29, corresponding to the keys which have been voted, advances the corresponding tapes through a distance to bring 80 the next higher numbers below the apertures 6.

It will readily be seen that the above construction permits of the voter changing his vote before leaving the voting-booth, as until then the vote is not completed. To change 85 his vote, it is only necessary for the voter to return the key voted to its original position and operate the key for preferred candidate.

In building up the machine by means of the sections, as has been already referred to, it is 90 necessary to connect the slides, which are in line with each other. This is readily accomplished by means of short strips 31, attached to the adjacent ends of slides 19, thus connecting said slides and causing them to reciprocate in unison.

The lower portion of each slot 18 in the slide is horizontal, so that in the return movement of the slides the fingers 17 are rotated in the reverse direction through a quarter-turn, bringing the keys 16 and fingers 17 back to their original position as the slides also resume their original position.

It is important to provide mechanism which will permit of a voter casting votes for a certain number of a group of candidates and no more. This is the case, for instance, in voting for Presidential electors, and this manner of voting is also often used in electing supervisors, judges, and the like. For this purpose we provide at the lower end of each voting-stem a stud 32, which rests against a pair of pins 33 on a sprocket-wheel 34. Said wheel has four pairs, equidistant from each other, of such pins. When the stem is raised, the stud 32 by pressure against the upper pin of the pair advances said sprocket-wheel through a quarter-turn, thereby advancing also a sprocket-chain 35. Said sprocket-chain runs over a series of such sprocket-wheels and also around two lower sprocket-wheels 36. It is evident that the sprocket-chain is advanced through a distance corresponding to the number of keys that have been voted, and if the advance of the sprocket-chain is limited so 115 will also be limited the number of keys of a group that may be voted. The amount of advance of the sprocket-chain is limited by means of a bar 37, attached to said sprocket-chain, which bar is attached to a tube 38, which 120

slides upon a rod 39, connected pivotally to the lower end of the lever 24. A pin 40 in said rod limits the distance to which the tube can be slid. This pin is adjustable in a series 5 of holes 51 in the rod 39. When the stem after being raised is turned in the act of voting, the stud 32 is withdrawn from contact with the pair of pins 33, so as to cause no obstruction to the further advance of the sprocket-chain when casting other votes. If the voter changes his vote and turns back the stem to its original position, the stud 32 will be brought back into contact with the two pins, and upon the stem dropping back to its normal position 10 15 said stud now pressing down upon the lower pin of the pair returns the sprocket-chain also to its former position.

When it is desired to permit only one of a group of candidates to be voted for, we provide on the lower end of each voting-stem, 20 loosely mounted thereon; a finger 41, which rests normally between the ends of sleeves 42, secured by means of screws 43 upon a stationary bar 44. When the stem is raised, said 25 finger 41 displaces steel balls 45 in a row in said sleeves. The amount of such displacement is limited by means of screws 46 in nuts 47 at the ends of the row of sleeves, so that when the finger has been inserted the channel 30 formed by said sleeves is completely blocked against the insertion of a finger on any other voting-stem.

The sprocket-chains 35 of different sections, in line with each other, may be connected to 35 move in unison by means of rods 48, attached to two adjoining sprocket-chains and in like manner the sleeves for the locking-balls may be formed into a continuous series from one section to another by removing the adjusting- 40 screws 46 and nut 47 from adjoining ends of series and replacing them by balls and sleeves 42, as shown in Fig. 6. It will be seen that the same motion of the lever 24 which returns the slides 19 to their original position also actuates the rod 39 to return the sprocket-chains and sprocket-wheels to their original position 45 in readiness for the next voter, as upon a forward rotation of the sprocket-wheels and chain the rod 37 is moved into engagement 50 with pin 40, carried by the rod 39, and upon movement of the levers 24 upon their pivots the lower ends thereof are carried toward the machine, forcing the rod 39 and rod 37 in the reverse direction, thereby returning the 55 sprocket-chains in the opposite direction to their normal position.

The vertical levers 24 are made adjustable as to their pivot-points, as shown at 49, so as to vary the distance through which the rods 60 at the lower ends of said levers are shifted for a given throw of the slides. This is necessary in order to vary the number of keys in a group which may be voted.

In Figs. 14 and 15 we have shown an alter- 65 native form of locking device in which lock-

ing-blocks 60 slide upon a rod 61 and are shifted by means of vertical slides 63, lifted by means of plates 64, attached to the lower end of stems 65, which in this instance are made much shorter than in the modification 70 first described.

Suitable framework is provided for holding the above parts in place. Thus the rollers for the tapes and bands are carried on brackets 70, the lower brackets being adjustable by 75 means of slots 71 in plates 72. These plates and the plates for the upper brackets are connected by angle-irons 73. Each section is thus complete in itself, and the sections when placed together are surrounded by the sides 80 and ends, as already explained.

We claim—

1. A voting-machine comprising voting-keys, a plate having the names of nominated candidates opposite said keys, rollers carrying 85 numbered tapes, means on the opposite side carrying bands for the names of unnominated candidates, shutters covering the said bands, stems for the keys, means actuated thereby to operate the shutters, fingers adapted to engage said rollers and means for shifting the keys to operate said fingers to move the said rollers, substantially as described.

2. A voting-machine comprising a row of voting-keys having stems, rollers arranged on 95 either side of said keys, means carried by one set of rollers for writing the names of unnominated candidates, means carried by the keys adapted to actuate the said rollers, and means whereby numbers of a group of candidates 100 may be voted for, said means being actuated by said stems, substantially as described.

3. A voting-machine comprising in combination voting-keys having stems thereon, a plate bearing the names of nominated candidates opposite said keys, rotatable means supporting numbered bands on one side of the keys, rotatable means carrying bands having names of unnominated candidates mounted at the other side of the keys, means carried by 105 the stems for actuating both of said means, and means mounted at each side of the keys for returning the same to position, substantially as described.

4. A voting-machine comprising a row of 115 voting-keys, names of nominated candidates on one side of said keys and opposite thereto, rollers on the same side carrying numbered tapes, rollers on the opposite side carrying tapes or bands for writing the names of un- 120 nominated candidates, pins on said rollers on both sides, fingers on the keys adapted to engage pins on the rollers on one side or the other, and means for shifting said keys to cause said fingers to advance said rollers, substantially as described.

5. In a voting-machine the combination with a row of voting-keys, a corresponding row of registering devices, rotatable means carrying bands on the opposite side of the 125 130

keys for names of scattering candidates, means carried by the keys for actuating the registering devices and the said bands when the keys are turned in one direction or the other, and 5 means for returning the keys to normal position after voting, substantially as described.

6. A voting-machine comprising a row of voting-keys, a plate having a row of names of nominated candidates opposite to said keys, a 10 row of tapes or bands on the opposite side of said keys, a row of shutters for exposing portions of said tapes or bands to write the names of scattering candidates thereon, stems for the keys, means carried by said stems for actuating 15 said registering devices when the keys are shifted in one direction and for actuating the tapes or bands when the keys are shifted in the other direction, and means operated by said stems when the keys are shifted in the 20 latter direction to withdraw said shutters, substantially as described.

7. A voting-machine comprising a row of voting-stems, a slide having slots, a finger on each stem arranged to be dropped into a slot 25 in the slide in the act of voting, a registering mechanism engaged by said finger when so dropped, means for shifting the slide, said slots being so shaped that the movement of the slide actuates the fingers to operate the 30 registering mechanism, tapes for the reception of names of scattering candidates mounted at the opposite side of the keys from the registering mechanism, and means carried by the keys to actuate the same, substantially as 35 described.

8. A voting-machine comprising a series of voting-stems, fingers thereon, slides having slots therein mounted at each side of the stems adapted to receive the said fingers, series of 40 rollers mounted at each side of the stems carrying pins thereon and corresponding with the slots in the said slides, bands mounted on the rollers for registering nominated candidates, bands mounted on the opposite series 45 for the names of un-nominated candidates, and means to actuate the same whereby the rollers are rotated, substantially as described.

9. A voting-machine comprising rows of voting-stems, slides corresponding thereto 50 mounted on each side of the stems, a lever for shifting all of said slides, registering mechanisms corresponding to the keys, means carried on the opposite side of the stems to said mechanisms for the names of scattering candidates, fingers arranged to be moved in the 55

operation of voting into slots in the slides, and means whereby the shifting of said slides by said levers actuates said fingers which have been so moved to advance the registering mechanisms, when the keys are turned in one direction and to operate the last-named means when the said keys are turned in the opposite direction, substantially as described. 60

10. In a voting-machine, the combination with sections, voting-stems mounted therein, 65 registering mechanisms mounted at one side of the stems, mechanisms for voting for un-nominated candidates carried at the opposite side, slides for operating both of said mechanisms, and means for voting for groups comprising sprocket-wheel, chains running there-over, means carried by the voting-stems to actuate the wheels and means to limit the advance of the said chain, substantially as described. 70

75 11. In a voting-machine, the combination with series of voting-stems, registering devices carried upon one side thereof, means for voting un-nominated candidates arranged at the opposite side thereof, slides mounted at 80 each side of the stems adapted to be engaged by the same, means for voting a group adapted to be actuated by the stems, and means to limit the movement of said means, substantially as described. 85

12. In a voting-machine, a series of voting-keys, stems thereon, registering mechanisms carried at one side of the stems, independent mechanisms at the opposite sides of the said stems, for voting for nominated candidates, 90 fingers carried by the stems adapted upon turning of the same to engage either of the said mechanisms to actuate the same, slides for returning said stems to normal position, means to actuate the slides, and means for group-voting adapted to be actuated by the stems, comprising sprocket-wheels, chains carried thereby, means adapted to be engaged by the stems to actuate said wheels, means for limiting the movement of the chains, and 95 means for returning said chains to normal position, substantially as described. 100

In witness whereof we have hereunto set our hands in the presence of two subscribing witnesses:
